(57) **CLAIM**

The ornamental design for a multipurpose golf tool with retractable brush and groove cleaner, as shown and described.

DESCRIPTION

FIG. 1 is a perspective front view of a multipurpose golf tool with retractable brush and groove cleaner in a closed position; FIG. 2 is a front elevation view of the multipurpose golf tool with retractable brush and groove cleaner in a closed position; FIG. 3 is a rear elevation view of the multipurpose golf tool with retractable brush and groove cleaner in a closed position; FIG. 4 is a left side elevation view of the multipurpose golf tool with retractable brush and groove cleaner in a closed position;

FIG. 5 is a right side elevation view of the multipurpose golf tool with retractable brush and groove cleaner in a closed position;

FIG. 6 is a top elevation view of the multipurpose golf tool with retractable brush and groove cleaner in a closed position; FIG. 7 is a bottom elevation view of the multipurpose golf tool with retractable brush and groove cleaner in a closed position; FIG. 8 is a perspective front view of a multipurpose golf tool with retractable brush and groove cleaner in an open position; FIG. 9 is a front elevation view of the multipurpose golf tool with retractable brush and groove cleaner in an open position; FIG. 10 is a rear elevation view of the multipurpose golf tool with retractable brush and groove cleaner in an open position; FIG. 11 is a left side elevation view of the multipurpose golf tool with retractable brush and groove cleaner in an open position;

FIG. 12 is a right side elevation view of the multipurpose golf tool with retractable brush and groove cleaner in an open position;

FIG. 13 is a top elevation view of the multipurpose golf tool with retractable brush and groove cleaner in an open position; and,

FIG. 14 is a bottom elevation view of the multipurpose golf tool with retractable brush and groove cleaner in an open position.
